UNITED STATES PATENT OFFICE.

MAXWELL E. RAMSEY, OF ST. LOUIS, MISSOURI.

MORTUARY BED.

Application filed February 12, 1927. Serial No. 167,646.

This invention relates to mortuary beds.

An object of the invention is to provide an improved mortuary bed having foldable end supporting frames comprising detachable sections, whereby parts of said end frames above the bed frame may be detached.

Another object of the invention is to provide an improved mortuary bed comprising 10 end frames and means for extending said frames to different vertical lengths, whereby the bed may be raised or lowered as desired.

Other objects will appear from the following description, reference being made to the drawing, in which

Fig. 1 is a side elevation of my improved mortuary bed.

Fig. 2 is an end elevation showing the 20 upper portion of the end frame detached.

Fig. 3 is an enlarged sectional view showing the construction of the end frames whereby the vertical length thereof may be extended or reduced, as desired.

25 Fig. 4 is a cross sectional view on the line 4—4 of Fig. 3.

The improved bed as shown comprises a bed frame end section 1 for the head of the bed, and a bed frame end section 2 for the 30 foot of the bed.

A transverse pivot rod 3 below the bed frame is connected to each side of the frame section 1 by a short link 4 and a long link 5; and is connected at each side to the foot 35 section 2 by a short link 6 and a long link 7. This construction permits one of the bed frame sections to be folded under the other, or in a relationship in which the two frame sections 1 and 2 are spaced apart a distance 40 approximately equal to the combined length of the links 4 and 6 at each side of the bed.

A pair of hollow supports 8 are pivotally connected to the outer ends of the bed frame sections 1 and 2 respectively. The pivotal 45 connection for each of said uprights 8 comprises a relatively short link 9 and a relatively long link 10, the ends of which links are pivotally connected to the uprights 8 and to depending plates 11 in rigid connection 50 with the sides of the frames 1 and 2 respectively. This permits the uprights to be folded under the respective bed sections 1 and 2 with which they are pivotally connected, or to be moved to position to support 55 the bed as shown. The parts are of such dimensions that the uprights 8 can be em-

braced between the two sections 1 and 2 when the latter are folded one under the other, as above described.

For each end of the bed, there is a detachable upper frame part 12 having a reduced extension 13 at each side designed and adapted to be received in the upper ends of the hollow uprights 8, there being shoulders 14 at the union of the extensions 13 with the frames 12 seating upon the upper ends of the uprights 8.

An extension element 15 telescopes into the lower end of each of the uprights 8 and is capable of various adjustments to extend or reduce the vertical length of the end frames of which the uprights 8 form a part. To each of the uprights 8 a latch lever 16 is pivoted, each of said latch levers having on its lower end an angular extension 17 extending under the lower end of the corresponding upright 8 and designed and adapted to engage in holes 18 in the extension elements 15 to hold the latter in their different adjustments in the uprights 8, as will be understood by reference to Fig. 3.

A rod 19 extends rigidly beyond each of the uprights 8 through a hole in the upper end of each latch lever 16 (Fig. 4). A coil spring 20 encircles each of the rods 19, the 55 pair of said springs being exerted to press the upper ends of the latch levers 16 away from the uprights 8 and to hold said latch levers in latching engagement with the parts 15.

90 My invention comprises means for simultaneously releasing the two latch levers 16 at each end of the bed. As shown, a pair of levers 21 are pivotally connected at 22 near their inner ends and have angular portions 23 at their ends, through which the rods 19 extend. These angular extensions are against the inner side of the levers 16. By pushing down the pivoted ends of the levers 21, the upper ends of the latch levers 16 are pushed outwardly toward the sides of the supporting frames in opposition to the springs 20 a sufficient distance to release the hooks 17 from engagement with the elements 15. This will permit the elements 15 to be moved to desired adjustments to obtain the desired vertical length of the end supporting frames of which the elements 15 form a part.

100 The lower ends of the elements 15 have castor rollers or wheels 24 swiveled thereto. Break elements 25 for said rollers are pivoted to the brackets 26 of the castor rollers 110

and are engageable with and releasable from the castor rollers to prevent said rollers from turning or to permit them to run along the floor or support upon which the bed is mounted, as desired.

From the foregoing, it will be seen that my improved mortuary bed possesses numerous advantages and obtains all of its objects and purposes in an efficient and simplified manner. The construction and arrangement of the parts may be varied within equivalent limits without departure from the nature and principle of the invention. I do not restrict myself in unessential particulars, but what I claim and desire to secure by Letters Patent is:—

1. A bed comprising an approximately horizontal frame, a pair of uprights supporting each end of said frame, an element telescoping in the lower end of each of said uprights, latches pivoted on said uprights for holding said elements in different adjustments, a rod extending inwardly from each of said uprights adjacent to said latches, springs for actuating said latches into latching engagement with said elements, and a pair of levers having their outer ends supported by said rods and engaging said latches and having their inner ends pivotally connected and being operative to release said levers from said elements.

2. A bed comprising an approximately horizontal frame, a pair of uprights supporting each end of said frame, an element

telescoping in the lower end of each of said uprights, a rod extending inwardly from each of said uprights, latches pivoted to said uprights for holding said elements in different adjustments and extending adjacent to said rods, springs on said rods between said latches and said uprights for holding said latches in engagement with said elements, and a pair of levers slidable on said rods and having their inner ends pivotally connected and their outer ends movable outwardly to release said latches from said elements.

3. A bed comprising an approximately horizontal frame, a pair of uprights supporting each end of said frame, an element telescoping in the lower end of each of said uprights, a rod extending inwardly from each of said uprights, latches pivoted to said uprights between said rods and the lower ends of said uprights and having their lower ends arranged to engage with said elements and their upper ends adjacent to said rods, springs on said rods between said uprights and said latches for holding said latches in engagement with said elements, and a pair of levers having their outer ends slidably supported on said rods and their inner ends pivotally connected and being operative to force the upper ends of said latches toward said uprights to release said latches from said elements.

MAXWELL E. RAMSEY.
